US00D874440S

(12) **United States Design Patent** (10) **Patent No.:** **US D874,440 S**
(45) **Date of Patent:** **** Feb. 4, 2020**

(54) **REMOTE CONTROL**

(71) Applicant: **SAMSUNG ELECTRONICS CO., LTD.**, Suwon-si, Gyeonggi-do (KR)

(72) Inventors: **Youngsun Shin**, Seoul (KR); **Taehan Kim**, Seoul (KR)

(73) Assignee: **SAMSUNG ELECTRONICS CO., LTD.**, Gyeonggi-Do (KR)

(**) Term: **15 Years**

(21) Appl. No.: **29/662,979**

(22) Filed: **Sep. 11, 2018**

(30) **Foreign Application Priority Data**

Jul. 25, 2018 (KR) 30-2018-0034475
(51) **LOC (12) Cl.** **14-03**
(52) **U.S. Cl.**
USPC **D14/218**

(57) **CLAIM**

The ornamental design for a remote control, as shown and described.

DESCRIPTION

FIG. 1 is a perspective view of a remote control, showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof; and,

FIG. 8 is another perspective view thereof.

The even-dash broken lines illustrating portions of the remote control form no part of the claimed design. The dot-dash broken lines in the figures illustrate a boundary of the claimed design and form no part of the claimed design.

1 Claim, 7 Drawing Sheets
